(57) **CLAIM**

The ornamental design for a hanging photo display, as shown and described.

DESCRIPTION

FIG. 1 is a front perspective view of the hanging photo display of the present invention;

FIG. 2 is a front elevational view of the hanging photo display shown in FIG. 1;

FIG. 3 is a rear elevational view of the hanging photo display shown in FIG. 1;

FIG. 4 is a left side elevational view of the hanging photo display shown in FIG. 1;

FIG. 5 is a right side elevational view of the hanging photo display shown in FIG. 1;

FIG. 6 is a top view of the hanging photo display shown in FIG. 1; and,

FIG. 7 is a bottom view of the hanging photo display shown in FIG. 1.

The drawings illustrate a hanging photo display as shown in the drawings. Stippling and/or contour lines are included in the various views of FIGS. 1-7 to depict surface curvature, flatness or other shapes.

1 Claim, 7 Drawing Sheets
